UNITED STATES PATENT OFFICE.

LEE R. CRUMB, OF NEW BERLIN, NEW YORK.

AUTOMOBILE FAN DEVICE.

Application filed December 5, 1923. Serial No. 678,727.

To all whom it may concern:

Be it known that I, LEE R. CRUMB, a citizen of the United States, residing at New Berlin, in the county of Chenango and State of New York, have invented certain new and useful Improvements in Automobile Fan Devices, of which the following is a specification.

My invention relates to an electric fan device, for use in connection with automobiles, particularly of the closed type, and has special reference to improvements in such a device disclosed in Patent No. 1,467,233, issued to me under date of September 4th, 1923.

An important object of the invention is to improve the construction of the fan device, in general, simplifying it, rendering it cheaper, stronger, and more efficient in operation.

A further object of the invention is to provide a device of the above mentioned character, adapted for use in connection with a ventilator whereby air may be drawn into or expelled from an automobile.

Other objects and advantages of the invention will be apparent during the course of the following description.

In the accompanying drawings, forming a part of this specification, and in which like numerals are employed to designate like parts throughout the same,

Figure 1 is a central vertical section through a fan device embodying my invention.

Figure 2 is a plan view of the motor frame,

Figure 3 is a bottom plan view of the motor support member,

Figure 4 is a central vertical section through a modified form of motor frame, and,

Figure 5 is a similar view of a third modified form of motor frame.

In the drawings, wherein for the purpose of illustration is illustrated a preferred embodiment of my invention, the numeral 10 designates the top of an automobile, as a whole, such as a closed car of the sedan type. This top may embody frame members 11 and 12, and an upper covering 13, suitably secured thereto. The intersecting frame members 11 and 12 may provide an opening leading into a ventilator, designated by the numeral 14. This ventilator is adapted to be opened and closed, in the usual manner.

The fan device embodies a motor frame or support 15, including a preferably flat annular plate 16, having a suitable number of openings 17. Formed upon the inner central portion of the plate 16 is a motor housing 18, which may be integral therewith. This housing has its lower end open and its top closed, excepting for the provision of air circulating openings 19.

The motor embodies field windings 20, which are rigidly mounted within the housing 18, and the armature 21 is rotatable within these field windings. This armature is carried upon a vertical armature shaft 22, the upper end of which is journaled in oilless fibre bearings 23, and its lower end is journaled in an oilless fibre bearing 24. This armature shaft carries thrust rings or washers 25, made of fibre, adapted to engage with the ends of the oilless fibre bearings, for taking up the end thrust of the armature shaft. I contemplate reversing the direction of rotation of the armature shaft for drawing air into the car or expelling the same therefrom, and for this reason it is desirable to have the two end thrust bearings.

The lower bearing 24 is carried upon a motor support member 26, preferably cup-shaped, and having an annular flange 27 at its top, to be secured to the plate 16 by screws 28 or the like. The motor support member 26 is provided with recesses formed therein for receiving tubular brush holders 28, slidably receiving spring pressed brushes 29, engaging the usual commutator 30. Current is of course supplied through the brushes in the usual manner. The support member 26, Figure 3, has air circulating openings 26', whereby air may discharge downwardly through the housing 18.

The armature shaft 22 projects downwardly below the supporting member 26 and has a propeller 31 rigidly mounted upon its lower end. This propeller is rotatable within a guard or cage 32, preferably formed of foraminous material, such as wire net. An imperforate plate 33 is mounted upon the inner portion of the guard 32 and is suitably secured thereto, and is concentric with the propeller and serves to deflect the air laterally. The guard 32 is provided at its edge with an annular flange 34.

The numeral 35 designates the inner lining of the top of the automobile, and this lining may be passed between the strips 11

and the plate 16, as shown, with screws 36 securing these parts together. The flange 34 may be secured to the outer edge of plate 16 by means of screws 37. If desired, the 5 lining 35 may be passed between the flange 34 and the plate 16.

In Figure 4, I have shown a modification of the motor frame. In this figure, the plate 16 is formed separate from the housing 18. The plate 16 has an upstanding annular flange 38, receiving the lower end of the housing 18 and detachably secured thereto by means of screws 39 or the like. In Figure 5, the housing 18 is shown as 15 equipped with a horizontal annular flange 40, and the annular plate 16 rests upon this flange, and may be secured thereto by screws 41 or the like.

In the operation of the device, the fan 31 20 may be driven in a manner to introduce air into the car and for effecting its proper circulation. The major portion of the air passes to the fan through the outer openings 17, surrounding the housing 18 to the motor. 25 Some of the air is drawn in through the inner openings 19 and passed in proximity to the armature of the fan, and is discharged through the openings 26'. When the ventilator 14 is open, the air may be drawn from 30 the exterior of the car and introduced into the same, or the motor may be reversed, and the air drawn from within the car and expelled to the exterior thereof. The motor is preferably series wound, while any suitable form of motor may be employed.

It is to be understood that the forms of my invention herewith shown and described are to be taken as preferred examples of the same, and that various changes in the 40 shape, size, and arrangement of parts may be resorted to, without departing from the spirit of my invention, or the scope of the subjoined claims.

Having thus described my invention, I 45 claim:

1. A fan device for use in the top structure of an automobile, such top structure embodying inner and outer walls and a frame between the walls, a housing for insertion between the walls and having a relatively wide plate extending about and beyond its margin, said plate having air circulating openings formed therein, means for securing the plate to the frame, a field winding mounted within the housing, an armature within the field winding, a substantially vertical armature shaft carrying the armature and extending downwardly beyond the same, a support member connected 55 with the lower end of the housing and carrying an end thrust bearing for the armature shaft, means for supplying current to the armature, a fan secured to the lower end of the armature shaft outwardly of the support member, and a guard covering the fan.

2. A fan device for use in the top structure of an automobile, such top structure embodying a frame having an air space therein, a housing projecting up into the air space and provided at its lower end with a plate extending laterally beyond the margin of the housing for a substantial distance, 70 said housing having a top provided with air circulating openings and having its bottom open, said plate having air circulating openings, a support member connected with the lower portion of the housing, a field winding held within the housing, an armature within the field winding, an upstanding armature shaft carrying the armature, an end thrust bearing carried by the support member and receiving the armature shaft, a commutator mounted upon the armature shaft, brushes carried by the support member and engaging the commutator, a propeller mounted upon the free end of the armature shaft, and a guard covering the propeller and connected with the plate.

3. A fan device for use in the top structure of an automobile, such top structure 90 embodying a frame having an air space therein, a housing projecting up into the air space and provided at its lower end with a plate extending laterally beyond the margin of the housing for a substantial distance, said housing having a top provided with air circulating openings and having its bottom open, said plate having air circulating openings disposed exteriorly of the 95 housing, a support member connected with the lower portion of the housing and having air circulating openings formed therein, a field winding held within the housing, an armature within the field winding, an upstanding armature shaft carrying the 100 armature, an end thrust bearing carried by the support member for the armature shaft, a commutator mounted upon the armature shaft, brushes carried by the support member engaging the commutator, a propeller mounted upon the free end of the armature shaft, a foraminous guard covering the propeller and having an attaching frame connected with the plate, an imperforate deflector plate mounted upon the 105 central portion of the foraminous guard in advance of the propeller, and a ventilator 110 above the air space.

4. In a fan device for use in the top structure of an automobile, such top structure embodying outer and inner spaced walls having an opening formed therein, a frame member between the walls at the opening, a motor housing mounted within the opening in spaced relation to the frame member 115 whereby air may circulate through the opening exteriorly of the motor housing, a motor mounted within the motor housing, and a fan secured to the inner end of the armature shaft of the motor.

5. A fan device for use with the top structure of an automobile, such top structure embodying spaced inner and outer walls having an opening formed therein which is in communication with the interior of the top structure and with the atmosphere exteriorly thereof, a motor mounted within the opening between the inner and outer walls, means for supporting the motor within the opening for retaining the same spaced from the edges of the opening whereby air may pass freely through such opening exteriorly of the motor, and a fan secured to the inner end of the motor.
- 10 6. The combination with a wall structure embodying spaced inner and outer walls forming a chamber therebetween, said inner and outer walls having openings formed therethrough leading into the chamber, a motor mounted within the chamber and openings, means for supporting the motor in position in spaced relation to the edges of the openings whereby air may circulate freely through such openings exteriorly of the motor, and a fan secured to the inner end of the armature shaft of the motor and projecting radially beyond the motor and extending across the air circulating passage exteriorly of the motor.
- 15 7. The combination with a wall structure embodying inner and outer walls forming a chamber therebetween, such walls having openings formed therein, a motor mounted within the chamber and openings, air circulating means serving to support the motor in place and retain the same spaced from the edges of the openings whereby air may
- 20 pass exteriorly of the motor, and a fan attached to one end of the armature shaft of the motor and extending laterally beyond the same and across the air passage exteriorly of the motor.
- 25 8. The combination with an automobile top structure embodying inner and outer spaced walls having openings formed therein, a ventilator element adapted to cover and uncover the opening formed in the outer wall, a motor mounted within the chamber formed by the inner and outer walls, air circulating means supporting the motor and retaining the same spaced from the edges of the openings whereby air may circulate freely exteriorly of the motor, and a fan carried by the armature shaft of the motor.
- 30 9. The combination with the top structure of an automobile embodying inner and outer walls having openings formed therein, a surrounding member mounted between the inner and outer walls adjacent to the edges of said openings, a ventilator member to cover and uncover the air passage provided by said openings and surrounding member, a motor mounted within the air passage, means for supporting the motor from the surrounding member and retaining the same spaced therefrom, said means being provided with air circulating openings, and a fan secured to the armature shaft of the motor and projecting radially therebeyond to operate in proximity to the air circulating openings.
- 35 In testimony whereof I affix my signature.

LEE R. CRUMB.
